(57) **CLAIM**

The ornamental design for a ice container, as shown and described.

DESCRIPTION

FIG. 1 is a top plan view of the ice container of the present invention showing my new designs;

FIG. 2 is a front elevational view thereof;

FIG. 3 is a right side elevational view thereof;

FIG. 4 is a bottom plan view thereof;

FIG. 5 is a rear elevational view thereof; and,

FIG. 6 is an inverted side elevational view thereof depicting the ice container in a stowed orientation with the phantom lines depicting solely environmental structure forming no part of the claim design.
